UNITED STATES PATENT OFFICE.

JOHN M. EWEN, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of Design No. 27,347, dated July 13, 1897.

Application filed June 15, 1897. Serial No. 640,939. Term of patent 14 years.

To all whom it may concern:

Be it known that I, JOHN M. EWEN, a citizen of the United States, residing at Chicago, in the county of Cook and State of Illinois, have invented and produced a new and original Ornamental Design for Prism-Plates, of which the following is a specification.

My invention relates to a design for prism-plates, and is illustrated in the accompanying drawing, showing a prism-plate containing my design.

A is the central body, substantially circular in cross-section, or at least bounded by curved lines. B B are prisms thereon.

C is one of the triangular corner-pieces, the side opposed to the central part being curved to correspond with the curvature of the cen-

tral part. D D are the prisms on such corner-pieces.

The five parts constitute substantially a square or rectangular piece.

The essential features of my invention are found in a prism-light consisting of a central prism-covered surface bounded by curved lines and four prism-covered surfaces bounded each by an inner curved line and by outer right lines, substantially as shown.

I claim—

The design for a prism-plate substantially as shown and described.

JOHN M. EWEN.
